UNITED STATES PATENT OFFICE.

OSCAR E. SCHNITZSPAHN, OF BUFFALO, NEW YORK.

COIN-COUNTING APPARATUS.

1,347,179.

Specification of Letters Patent. Patented July 20, 1920.

Application filed August 18, 1917. Serial No. 186,924.

To all whom it may concern:

Be it known that I, OSCAR E. SCHNITZSPAHN, a citizen of the United States, residing at Buffalo, in the county of Erie and State of New York, have invented new and useful Improvements in Coin-Counting Apparatus, of which the following is a specification.

This invention relates to an apparatus for accurately counting a mass of disarranged coins and spreading the same out for inspection and then depositing them in stacking tubes, the primary object of this improvement being to reduce the time and effort necessary for this operation.

In the accompanying drawings:

Figure 1 is a perspective view of the counting apparatus embodying my invention. Figs. 2 and 3 are vertical transverse sections taken on lines 2—2 and 3—3, Fig. 4, respectively. Fig. 4 is a top plan view of the apparatus with the top tilting bars and coin tracks omitted. Fig. 5 is a vertical longitudinal section taken on line 5—5, Fig. 4. Fig. 6 is a perspective view of the mandrel used in making the paper stack-retainers or coin tubes.

Similar characters of reference indicate corresponding parts throughout the several views.

My improvements are associated with a coin spreading device which comprises an upwardly flared feed tube 1 open at the top and provided with a longitudinal controlling bar 2 at the bottom thereof permitting the tube to be removed from the apparatus and coins 36 poured therein without permitting said coins to drop straight through said tube. A transverse notch 3 is provided at the rear and lower end of said tube to permit the lowermost coin to be slid out horizontally and rearwardly therefrom. After the feed tube has been loaded with coins, the controlling bar, which has a forward longitudinal extension 4 forming a guide shoe, is placed longitudinally in the rear end of one of the upwardly opening channel-shaped counting tracks, racks or rails 5 and then the tube is moved forwardly. As said tube passes successively over the pairs of teeth or lugs 6 which project upwardly from the flanges of said track, the coins are retained one after another by said lug pairs, the number of coins deposited on each track de-

pending on the number of lug pairs. The 55 tube is then picked up and the controlling bar inserted into the rear end of the channel of the next track and again moved forwardly and so on continuously, depending on the number of tracks or on the number 60 of coins to be counted. The invention so far described is shown in Letters Patent of the United States #992,963, dated May 23, 1911.

In this prior patent the tracks are arranged on the upper surface of a fixed counting board necessitating first tipping the board transversely to slide the coins laterally away from the lugs and then inclining said board longitudinally to slide the coins off the same.

My improvements are designed to facilitate discharging the coins from the counting tracks and to deliver the same into coin tubes or other receptacles and in their preferred form the same are constructed as follows:—

7 represents a main frame having the form of a box which comprises two longitudinal walls 8, front and rear end walls 9, and a top 10. The top of the frame is provided with a longitudinal slot in which are arranged one or more horizontal longitudinal tilting bars 12, two of such bars being shown as an example. Each of these tilting bars is pivoted on the frame adjacent to one of its longitudinal edges so as to be capable of depressing its opposite longitudinal edge. This pivotal connection preferably comprises two movable hinge leaves 13, 13 secured to opposite ends of the tilting bar and connected by pintles 14, 14 to fixed hinge leaves 15—15 on the adjacent parts of the frame, as shown in Figs. 2, 3, 4 and 5. One of the coin counting tracks or rails is arranged lengthwise on each of these tilting bars adjacent to the heel thereof so that when the toe thereof is depressed the coins which have been spread out over the respective tracks are caused to slide laterally and downwardly off the same. It will be noted that the pintles 14 are some distance in front of the rear longitudinal edge of the tilting bars, so that not only is the outer edge of each coin allowed to drop when the track is tilted but the opposite or inner edge of the coin is given a decided upward kick resulting in its dislocation even when very sticky. Various means may be employed for rocking the tilting bars, those shown in

the drawings being satisfactory and comprising a vertically movable slide 35 guided in a way 16 on the inner side of the frame below the top thereof and provided with an inwardly projecting arm 17 and an outwardly projecting handle or finger piece 18. The inner arm 17 is connected with the movable hinge leaves of the tilting bars by links 19 and the handle projects outwardly 10 through a vertical slot 20 in the frame so that the same may be manipulated from the exterior of the frame. 21 represents a spring which connects the slide with the main frame and operates to yieldingly hold 15 the slide in an elevated position and the tilting bars and tracks in a horizontal position. As the coins drop from each tilting bar the same fall into a runway or guideway which is arranged below the companion tilting bar 20 and which directs the same into a suitable receptacle. Each of these guideways comprises two longitudinal side walls 22, 22, a bottom 23 inclining from the upper rear or receiving end to the lower front delivery end, a rear end wall 24 and a front end wall 25 having outlet openings 26.

The bottoms of both coin runways are preferably formed on a removable panel 11 which also carries the front and rear walls 30 of both runways, both longitudinal walls of one runway and one longitudinal wall of the other runway while the other longitudinal wall of the last mentioned runway is fixed on the frame. The panel and the parts 35 mounted thereon are held in position on the frame by means of a turn button 27 pivoted on the underside of the panel and engaging at its opposite ends with shoulders 28, 28 on opposite sides of the frame. This 40 arrangement permits the quick removal of the bottom panel and the longitudinal walls secured thereto thus exposing all parts, so that any sticking or jamming of the coins, which might possibly occur, can be easily remedied. The open upper end of each 45 coin runway enlarges or flares upwardly throughout the length thereof so that the coins enter the same readily, upon depressing the companion tilting bar. Each of the runways also gradually enlarges from its rear end toward its front end by diverging its side walls in this direction, thereby 50 preventing the coins which roll edgewise down the inclined bottom thereof from becoming jammed in the guideway and clogging the same.

As the coins fall from the tracks and tilting bars into the coin runways they land edgewise on the bottom thereof and roll 55 down the same to the discharge end into a chute 29 which receives the coins from both runways. From this chute the coins may be delivered into a bag or other receptacle of any suitable construction. If the coins 60 being counted are to be stacked and wrapped

into rolls or packages, a stacking tube 30 which is provided with an upper flared end adapted to be arranged below the outlet of the chute and receive the coins from the latter is employed for this purpose. This 70 stacking tube is preferably detachably connected with the chute by providing the latter on its underside with a curved channel-shaped seat 31 which receives the rim of the stacking tube.

The coins feed or drop into the stacking tube on their flat side and thus automatically stack themselves. At its side the stacking tube is provided with a door 32 which upon being opened permits the removal of 80 the stack of coins therefrom. For further facilitating the wrapping of coins into rolls or packages, a previously prepared paper tube 33 of the proper size and closed at one end may be placed inside of the stacking 85 tube, so that the coins will feed directly into this paper tube through its upper or open end. After removal from the stacking tube the roll may be completed by simply closing or crimping in the ends.

The wrapping tubes may be formed around a cylindrical mandrel 34 shown in Fig. 6, or in any other suitable manner.

In operating the apparatus, the coins are dumped into the feeding or counting tube 1, whose lower end is moved successively forward over each counting track, rack or rail so that the pairs of lugs of the same remove a definite number of coins from the feed tube which are now spread out flat on the racks, so that any spurious pieces or vacant places can be quickly detected and cared for. The fingerpiece or handle 18 is then depressed causing the tilting bars to drop their load into the runways down 100 which the coins roll into the chute 29 and then drop into the tubular paper wrapper 33 inserted into the stacking tube 30. The door of the latter is then opened, the paper tube which is now filled with a stack of 105 coins is removed and the upper end of the wrapper folded inwardly, thereby completing the package or roll of coins. This machine permits extreme rapidity and reliability of counting, examining and wrapping 110 coins without necessitating a separate apparatus for each size of coin inasmuch as one apparatus will take care of a number of sizes within certain limits, while greatly varying sizes merely require separate sets of 115 tubes.

I claim as my invention:

1. A coin counter comprising a vertically swinging rack adapted to support the coins deposited thereon so that their flat sides are 125 arranged horizontally, and a guide-way into which the coins are discharged directly from said rack upon tilting the latter and which is of such width that the coins are held with their flat sides in a vertical position 130

and which has an inclined bottom upon which the coins roll at their edges lengthwise of said guide-way.

2. A coin counter comprising a frame, a 5 tilting bar pivoted on said frame to turn vertically, a coin receiving rack mounted on said bar, a runway adapted to receive the coins from said rack upon tipping the same and the tilting bar, and means for turning 10 said bar comprising a vertically movable slide guided on the frame and provided with a handle, a link connecting said slide with said bar, and a spring connected with said

slide and frame and operating to hold said rack and associated parts yieldingly in their 15 normal position.

3. A coin counter comprising a rack upon which the coins are adapted to be placed, means for turning said rack vertically, and a runway which is adapted to receive the 20 coins on their edge from said rack and direct the same to a receptacle and which gradually increases in width from its receiving end toward its delivery end.

OSCAR E. SCHNITZSPAHN.
